UNITED STATES PATENT OFFICE

141,718

DESIGN FOR A COMBINED FAUCET AND SOAP DISH

Cecil G. Blank, Toledo, Ohio, assignor to Barnes
Manufacturing Co., Mansfield, Ohio, a corpo-
ration of Ohio

Application January 17, 1945, Serial No. 117,486

Term of patent 14 years

(Cl. D4—3)

To all whom it may concern:

Be it known that I, Cecil G. Blank, a citizen
of the United States and a resident of Toledo,
Lucas County, Ohio, have invented a new, origi-
nal, and ornamental Design for Combined Faucet
and Soap Dish, shown in the accompanying
drawing.

In the drawing:

The figure is a perspective view of a combined
faucet and soap dish, embodying my new design.

I claim:

The ornamental design for a combined faucet
and soap dish, substantially as shown.

CECIL G. BLANK.
